Hector Glazner
Attorney

UNITED STATES PATENT OFFICE.

MICHAEL HOFFMAN, OF LOS ANGELES, CALIFORNIA.

LUG-REMOVING DEVICE.

Application filed October 13, 1924. Serial No. 743,281.

To all whom it may concern:

Be it known that I, MICHAEL HOFFMAN, a citizen of the United States, residing at Los Angeles, county of Los Angeles, and State 5 of California, have invented a certain new and useful Lug-Removing Device, of which the following is a specification.

My invention relates to a means for removing members, elements, and other appurtenant parts from bodies to which they are attached, secured, or riveted; and it has especial reference to a tool or device for removing from bands used in certain types of motor vehicle transmissions, the lugs 10 fastened thereon usually by rivets, to enable the bands to be removed from the housing without disturbing or dismantling it.

The object of the invention is to provide a simple tool for the purpose stated, by which 20 the lugs or other riveted parts may be pried loose and separated from the bands and while such bands are in position in the housing; and which may be conveniently inserted into the housing and operated from 25 without.

Other objects will appear from the specification following, in connection with the accompanying drawing, which illustrates a device for carrying out the above objects, and 30 in which,

Fig. 1 is a transverse section through the housing of a motor vehicle transmission showing the invention as actually used;

Fig. 2 is a sectional view showing the assembled parts of the device;

Fig. 3 is a fragmentary plan view; and

Fig. 4 is a plan detail of the lever used in connection with the device.

Referring to the drawing, it will be observed that the invention embodies generically a wedge or other element for prying loose an attached member, with a means for gripping or engaging the object to which such member is attached and a means for operating the lever.

As shown in the preferred form in the drawing, the wedge member 1 is a flat, slightly curving member having at one end thereof an acuminate or thinned edge 2, for facilitating the insertion and entry thereof between the lug 3 and band 4, to which the lug is riveted. The acuminate or thinned edge 2 is provided with an inwardly extended, substantially V-groove 5, the respective 55 branches of which encompass or straddle the

holding means, and the upper faces of which are preferably beveled, as at 6, to produce a prying or lifting action by a gradual wedging of the thinned edge 2 between the connected objects to be separated. The other 60 end of said wedge member 1 is conjoined to the inclined face 7 of a thrust block or member 8, the connection of the wedge member with the block 8, being such that the former may have limited relative movement by 65 which the wedge member may adjust itself to changes during the operation thereof. For the purpose of effecting an association of the wedge member with the member 8 in the manner stated, pins 9 are provided in 70 the member 8, such pins extending through elongated slots 10, in the other end of said wedge member 1, and provided with heads 11, to prevent dissociation of the lever from the member.

In the drawing, I have shown a device of the present invention in use with a transmission band of usual type and construction, and provided with slotted lugs 3, above referred to. While this invention is applicable to the purpose of removing these lugs, it will be understood that this disclosure is not intended to limit the device to that use and that the reference in connection with such specific use, is illustrative merely.

The block or member 8 aforementioned, is provided with a longitudinal smooth bore 13, for accommodating an externally threaded shank 14, carrying at one end thereof a means for engaging one of two conjoined objects that are to be separated. Such means may be a slotted device, as shown at 15, or any other that will positively and securely hold the engaged objects, while the wedge member 1 is being operated to separate the 95 same. I have referred to a slotted device merely because of the convenient adaptation to the lugs 3, but any device, contrivance or other means that engages one of two or more conjoined objects to be separated, 100 is comprehended within this disclosure.

The threaded shank 14 is held against relative rotation during the operation of the tool, by a stud or key 16, penetrating the block 8 at right angles to the bore 13 therein 105 and extending into a longitudinal groove or key-way 17 in said shank. The block 8 is movable longitudinally relative to said shank 14, by a hollow tubular body 18, provided with internal threads 19 arranged for co- 110

operation with the external threads of said shank 14. The hollow tubular body is provided with a handle 20, for operating same.

Attention is called to the threads 14' of the shank 14. The form of these threads is substantially that of a saw tooth, for the very important purpose of presenting to the thrust area practically a flat surface.

It will be noted that the thrust of the wedge member 1 occurs against a shoulder 21, on said block 8, and immediately in the rear of said wedge member 1, the pins 9, referred to above, serving chiefly to hold said wedge member 1, associated with said block, without sustaining any great amount of pressure.

In practice, the slotted end 15, of the shank 14, is engaged with one of two or more objects to be separated. In the accompanying illustration, this engagement of the slotted end is shown with one of the lugs usually riveted to a transmission band. The wedge member 1, at the same time is introduced between the lug and the band. Thereupon the block 8 is caused to move by the manipulation of the body 18, such movement forcing the wedge member between the objects and eventually separating them. It will be seen that the greater the pressure exerted against the block, the greater will be the resistance offered by the object engaging means.

What I claim, is:

1. A device for removing lugs from transmission bands, comprising a shank having

means for engaging a lug, a member operable on said shank, an elongated wedge loosely connected to said member, and means for operating said member on said shank to force said wedge between the lug and band. 49

2. A device for removing lugs from transmission bands, comprising a shank formed with a slotted end for engagement with a lug, a member on said shank having an inclined bottom and a shoulder, a wedge loosely connected with the inclined bottom of said member and bearing against said shoulder, and means to operate said member to force said wedge between the lug and band. 50

3. A device for removing lugs from transmission bands, comprising a threaded shank having a slotted end for engaging a lug, a member movable on said shank and having an inclined bottom terminating in a shoulder, a wedge means connecting said wedge to the inclined bottom of said member to have relative movement, and means for operating said member to force said wedge member between the lug and band. 55

4. A device for removing lugs from transmission bands, comprising a threaded shank having at one end a slotted means for engaging a lug, a carrier on said shank, a wedge connected to said carrier to have relative movement, and means to operate said carrier to force said wedge between the lug and band. 60 65

In testimony whereof I have set my hand.
MICHAEL HOFFMAN.
